DESIGN FOR A TOKEN DISPENSER

Walter J. Taylor, Kansas City, Kans.

Application August 2, 1937, Serial No. 70,780

Term of patent 3½ years

To all whom it may concern:

Be it known that I, Walter J. Taylor, a citizen of the United States, residing at Kansas City, in the county of Wyandotte and State of Kansas, have invented a new, original, and ornamental Design for Token Dispensers, of which the following is a specification, reference being had to the accompanying drawing, forming a part there-

of, in which the figure is a front perspective view of a token dispenser showing my new design. The rear side of the device is substantially plain.

I claim:

The ornamental design for a token dispenser, as shown and described.

WALTER J. TAYLOR.
